TWO STROKE PISTON-CONTROLLED
ENGINE

Alfred Lesage, Schweinfurt, Germany

Original application June 8, 1934, Serial No. 729,550, now Patent No. 2,046,392. Divided and this application October 23, 1935, Serial No. 46,418. In Germany June 16, 1933

2 Claims. (Cl. 123—65)

This application is a division of my prior application, Serial No. 729,550, filed June 8, 1934, Patent No. 2,046,392, July 7, 1936.

The invention relates to two-stroke piston-controlled engines in which the admission and exhaust apertures are disposed at opposite sides of the engine cylinder, while the channels communicating with the apertures are in their main conduit obliquely directed towards the cylinder head. Further the said channels enter the cylinder in such angular relation that the scavenging gases will pass the cylinder space practically on a helical path and sweep all points of its interior.

15 The object of the invention is to provide further leading means for the gas stream within the cylinder itself with the aim to increase the scavenging effect.

This object is attained by giving the piston head the shape of a roof the ridge of which is disposed with respect to the admission and discharge channels in a preferably acute angle, so that the gases are directed not only towards the cylinder head but also deflected laterally to opposite points of the cylinder wall far of the ports. Another characteristic useful for the smooth flow and reversal of the gas stream is the construction of the cylinder head dome or roof shaped giving the upper part of the gas stream the desired helical flow.

30 These and other objects of the invention will appear as the description thereof proceeds and reference may be had to the appended drawing which illustrates two embodiments of the novel disposition intended for producing the said scavenging process. In said drawing, which forms a part of this specification,

Fig. 1 by a vertical sectional view of an engine cylinder illustrates the subject matter of the invention;

40 Fig. 2 is a vertical sectional view of the cylinder and the piston in a plane turned through 90° about the axis as compared with Fig. 1;

Fig. 3 illustrates a section through the cylinder on the line C—D of Fig. 2 and

45 Fig. 4 shows a similar cross section of a cylinder the exhaust opening of which is subdivided, according to the second embodiment of the invention.

50 Like numerals denote like or similar parts throughout all figures of the drawing.

In the embodiment represented by Figs. 1 to 3 the inlet or admission duct 10 is disposed in a tangential and slanting direction with regard to the cylinder head 13 in the cylinder wall, and

opposite the said duct there is arranged, also in a tangential and slanting direction with respect to the head 13, an exhaust duct 11. The axes of the channels 10 and 11 are in parallel planes, as for example represented by Fig. 3. 5 Thus the gases flow through the duct 10 tangentially and in an inclined direction upward towards the cylinder wall 12 at points laterally and above the exhaust duct 11 so that the current of gas is deviated towards the cylinder 10 head 13 and helically to the mid of the cylinder 12 so as to push the exhaust gases towards the center of the cylinder and downward towards the exhaust port 11 disposed diametrically opposite to the said inlet port 10. 15

In the above-described embodiment the cylinder head is so shaped that the gas current is not only turned downward but also deflected towards the center of the cylinder so that a helical path is imposed to the flow and thus a perfect scavenging action is secured in the cylinder. As shown by Fig. 1, the cylinder head is vault-shaped, e. g., roof-shaped but stress should be laid upon any sharp corner being avoided, as seen from the drawing. The shape should 20 particularly be adapted to the path of flow desired.

The head of the piston is roof-shaped, while the ridge or top 16 thereof, as indicated by the dot and dash line in Fig. 3, is suitably disposed 30 in more or less acute angles with the inlet direction. On the inclined surface adjacent to the inlet duct 10 the fresh gases are deflected upward and laterally, as stated herebefore, but the other side of the piston head slopes towards the 35 exhaust duct 11; therefore the ridge 16 separates the two branches of the current of gases from each other.

In the embodiment shown in Fig. 4 the inlet passage is at an acute angle to the ridge of the 40 piston, the position of which is indicated by the dot and dash center line, and the exhaust passage is offset with respect to the inlet port, as in Fig. 3, but it is at an acute angle to the inlet passage and is enlarged and subdivided. 45 The flow of the gases in the cylinder also takes place on helical lines but the discharge of the exhaust gases is at the same time improved.

Invention claimed—

1. In a two-stroke combustion engine, the combination with a roof-headed cylinder, of an inlet passage on one side of the cylinder and an outlet passage formed on the opposite side of the cylinder in staggered relation to the inlet passage, the axes of said passages being dis- 50 55

- posed in substantially parallel planes and directed towards the head of the cylinder, a piston working in said cylinder, and roof-shaped guides formed on said piston and disposed transversely 5 of said passages when the piston is at the end of the expansion stroke, the ridge of said roof-shaped piston head being disposed in acute angles with respect to the axis of the inlet passage.
- 10 2. In a two-stroke combustion engine, the combination with a roof-headed cylinder, of an inlet passage on one side of the cylinder and an

outlet passage formed on the opposite side of the cylinder in staggered relation to the inlet passage, the axes of said passages being directed towards the head of the cylinder, a piston working in said cylinder, and roof-shaped guides 5 formed on said piston and disposed transversely of said passages when the piston is at the end of the expansion stroke, the ridge of said roof-shaped piston head being disposed in acute angles with respect to the axis of the inlet passage. 10
